UNITED STATES PATENT OFFICE.

ALEXANDER T. BROWN, OF SYRACUSE, NEW YORK.

TYPE-WRITING MACHINE.

No. 799,627.

Specification of Letters Patent.

Patented Sept. 19, 1905.

Application filed March 5, 1904. Serial No. 196,648.

To all whom it may concern:

Be it known that I, ALEXANDER T. BROWN, a citizen of the United States, and a resident of Syracuse, in the county of Onondaga and 5 State of New York, have invented certain new and useful Improvements in Type-Writing Machines, of which the following is a specification.

My invention relates more particularly to 10 type-bars and hangers for writing-machines, and has for its main objects the provision of means for guiding and steadyng the type-bar at the printing moment and the construction of the type-bar and the hanger and their 15 mounting.

To these main ends the invention consists in the various features of construction and combinations and arrangements of parts hereinafter more fully described, and particularly 20 pointed out in the appended claims.

In the accompanying drawings, Figure 1 is a rear elevation, partly in section, of sufficient of a type-writing machine to show my invention and embodying the latter. Fig. 2 25 is a central vertical longitudinal section of such a machine. Fig. 3 is an enlarged horizontal section on the line *x x* of Fig. 2 and looking in the direction of the arrow at said line.

In the several views the same part will be 30 found designated by the same numeral of reference.

1 designates the base of the machine, 2 the top plate, supported on posts 3, rising from the base, and 4 the platen, which is shown 35 only diagrammatically.

The key-levers 5 within the base of the machine may be pivoted at their rear ends, as at 6, and may be furnished with the usual restoring-springs 7. In the present instance 40 a bell-crank 8 is pivoted at 9 directly to a key-lever 5, and the lower slotted end 10 of said bell-crank engages a transverse fulcrum-rod 11, as in prior machines. The upper end of the bell-crank is pivoted at 12 to the rear 45 end of a connecting-link 13, and its forward end is pivoted at 14 to an ear on the upper edge of a type-bar 15, which in this case is shown as provided with two types—one upper and one lower case. The type-bar may be 50 provided with a returning-spring 15^a. The type-bar is pivoted at 16 to or in a hanger 17, which is fixed by a screw 18 to a segment or support 19, which is vertically arranged in the usual manner of front-strike machines 55 and which may either be secured to the framework at its opposite ends, as by screws 20,

or may be arranged to shift up and down for the change of case. In the present instance, for convenience solely, the segment is shown as fixed, and by the dotted lines in Fig. 2 the 60 platen is shown as shiftable for upper-case printing. The rear end of the type-bar is formed or provided with an extension, arm, or tailpiece 21, which normally when the type-bar is at rest against its supporting-pad 22 65 projects rearwardly and substantially in the line of the bar. This arm 21 is adapted just before the end of the printing stroke to enter a notch or bifurcated portion 23 in the hanger 17, such portion being formed and arranged 70 at the lower end of the hanger. The said bifurcated portion is preferably formed with a flaring mouth 24 to enable the ready entrance of the arm 21 and with parallel walls 25 matching the sides of the arm to guide and 75 center or steady the bar just before and at the time of the type impression.

The hanger is preferably made of one solid piece of metal with its upper end forked at 17^a to receive the hub end or pivotal portion 80 26 of the type-bar, although, as is common in this art, the hanger may be made plain and the type-bar bifurcated to straddle the hanger. The type-bar is drilled and likewise the cheek-plates of the hanger for the passage through 85 the coinciding holes of the rivet or pivot-pin 16, which may be headed at its opposite ends. The type-bar and hanger are so connected together that the former shall have a close fit but yet be freely acting. With such a joint 90 there is a liability of the types printing out of alignment, and hence the provision of the arm 21 and its co-operating guide, notch, or jaws.

In action when a key-lever is depressed the upper end of the bell-crank is swung rearwardly, and through the action of the connecting-link 13 the type-bar is pulled upwardly and rearwardly about the pivot 16. During this movement the arm 21 swings downwardly and forwardly, and its outer extremity at near the end of the printing stroke passes through the flaring mouth 24 and then in between the parallel jaws of the guiding device and is there situated at the time the type strikes the paper on the platen. 100 105

While I prefer to have the cross-section of the arm 21 parallel-sided and to provide in the guiding portion of the hanger parallel-sided jaws, nevertheless the latter may be dispensed with and the cross-section of the arm may be 110 differently shaped, it being only necessary that the arm and the guiding device co-oper-

ate to steady and direct or guide the bar at the time of printing.

Preferably the arm 21 is made of appreciable length, and the guiding device is located at a corresponding distance from the pivotal point of the type-bar, so as to produce, in effect, a wide support or bearing for the type-bar when the impression is made. It will be observed that the distance from the pivot 16 of the type-bar to the guiding device is in this instance about one-third the length of the type-bar proper, and when the free end of the arm co-operates with the said guiding device the type-bar is caused to print true or in alinement. While I have referred to the different proportions, of course it will be understood that they are in no wise essential. It will also be understood that by the employment of the guiding device described the type-bars will print in alinement. The use of the arm 21 does not add perceptibly to the touch of the type-bar action, since it is located on the opposite side of the pivot from the type-bar proper, and hence has a counterbalancing or upwardly-lifting tendency thereon.

The type-bar hanger is preferably secured to the segment or support between the type-bar pivot and the alining or guiding device, and for this purpose the said hanger is formed at about its middle with a perforation or hole 27 for the passage therethrough of the retaining-screw 18. The hangers are made as narrow as possible, so as to take up little room on the segment; but at the perforated portions these hangers are made slightly wider than the body portion in order to obtain as large a hole as possible and the use of a good-sized securing-screw, the head of which bears upon the metal surrounding the said hole when the hangers are in position. The widened portions of adjacent hangers are arranged to alternate or are staggered, as indicated in Fig. 1, the segment being drilled with two parallel curved series of holes 28 for the hanger-screws, the said holes being threaded to receive the threaded ends of said screws.

The hangers are constructed so as to be radially adjustable to facilitate the alinement of the type-bars after the assembling thereof. To this end the holes 27 in said hangers are made elongated, and this will enable the hangers, with their integral guides, to be moved slightly transversely of the segment on lines radiating to the printing-point and then secured by the set-screws 18 after the type-bars have been properly adjusted.

While I have described particularly a single hanger, type-bar, and its associated guide, it will be understood that a full system of radially-arranged type-bars and hangers are provided and that each hanger is provided with a guide for co-operation with the arm 21 on its associated type-bar and that said guides are each located in the same radial plane that

the type-bar swings in and outside the segmental line formed by the pivots of the type-bars and in the rear of the segment. It will also be seen that the guiding member or extension 21 moves in an opposite direction from its associated bar as the bar approaches the printing position; that the type-bar proper and the extension 21 may be regarded as a type-bar pivoted intermediate of its ends and carrying a type or types on one end and a guiding member at the other end, and which is brought into co-operation with its associated guiding means just before the bar reaches the printing position, so that the bar is free from any retarding effect of the guiding means except possibly at the last portion of the stroke of the bar, when it has acquired its greatest speed. It will likewise be observed that in the normal position of each type-bar the bar itself extends to the front of the segment 19, whereas the arm 21 extends to the rear of the segment, and that said arm moves downwardly into co-operation with its associated guide as the body of the bar moves upwardly to the printing-point.

Various changes may be made without departing from the spirit of my invention, and in place of the type-bar-actuating devices shown any other suitable actuating means may be employed.

What I claim as new, and desire to secure by Letters Patent, is—

1. In a front-strike type-writing machine, the combination of a substantially vertical segment, a hanger secured to the rear side of said segment, an upwardly and rearwardly swinging type-bar pivoted to said hanger and having a rearwardly-extending tailpiece substantially in line with the type-bar, and a forked guide at the rear of said segment.

2. In a front-strike type-writing machine, the combination of a substantially vertical segment, an upwardly and rearwardly swinging type-bar that is pivoted in the rear side of said segment and has a tailpiece that extends rearwardly from said type-bar substantially in line therewith, a link that extends above the tailpiece and is connected to the type-bar for actuating it, and a forked guide that co-operates with said tailpiece at and near the last portion of the printing stroke of the type-bar.

3. In a front-strike type-writing machine, the combination of a substantially vertical segment, an adjustable hanger, an upwardly and rearwardly swinging type-bar that is pivoted to said hanger in the rear of the segment and has a tailpiece that extends rearwardly from said type-bar substantially in line therewith, a link that extends above the tailpiece and is connected to the type-bar for actuating it, and a forked guide carried by and adjustable with the hanger and which co-operates with said tailpiece at and near the last portion of the printing stroke of the type-bar.

4. In a front-strike type-writing machine, the combination of a substantially vertical segment, a series of segmentally-arranged hangers secured to the rear face of said segment, a series of upwardly and rearwardly striking type-bars pivoted to said hangers and each provided with a rearwardly-extending tailpiece that is substantially in line with its type-bar, and a forked guide on each hanger and with which the tailpiece on the

associated type-bar is adapted to coöperate at and near the last portion of the printing-stroke of the type-bar.

Signed at Syracuse, in the county of Onondaga and State of New York, this 1st day of 15 March, A. D. 1904.
